UNITED STATES PATENT OFFICE.

HOMER E. ADAMS, OF FORT WORTH, TEXAS.

ELECTRIC MOTOR.

1,137,729.

Specification of Letters Patent.

Patented May 4, 1915.

Application filed January 19, 1914. Serial No. 813,046.

To all whom it may concern:

Be it known that I, HOMER E. ADAMS, a citizen of the United States, residing at Fort Worth, in the county of Tarrant and State of Texas, have invented certain new and useful Improvements in Electric Motors, of which the following is a specification.

My invention relates to electric motors, and its object is to provide an electric motor 10 that will operate with equal efficiency on either direct or alternating current.

Another object is to provide an electric motor of the character described that may be wound and proportioned to develop any 15 reasonable power, and which will involve no greater expense either in construction or operation than such motors as are now in common use.

A further object is to provide an electric 20 motor that will operate on either direct or alternating current and will have an equally strong starting torque in either case.

With these and various other objects in view, my invention has relation to certain 25 novel features of the construction and operation, an example of which is described in the following specification and is illustrated in the accompanying drawings, wherein:

Figure 1 is a diagrammatic view of the 30 motor in front elevation, showing the manner of winding the armature and field magnets together with all electrical connections. Fig. 2 is a development of the armature winding, showing the directions of current 35 in the conductors at the moment when each brush has contact with two commutator segments. Fig. 3 is a similar view, showing the circuit relations of the armature conductors at the moment when each brush has contact 40 with only one commutator segment. Fig. 4 is a simplified diagram, explanatory of the motor connections.

Referring now more particularly to the 45 drawings, wherein like reference characters designate similar parts in all the figures, the numeral 1 denotes the field magnet yoke, preferably of the common annular form, and 2 designates the field magnet cores, which are interiorly mounted upon the yoke 50 in the usual well known manner. These projecting cores are six in number, their windings being respectively designated by the letters A, A', B, B', C, and C'. The three uppermost field magnet windings 3 are

respectively series connected with the three 55 opposite lower windings 3, and are arranged to produce an opposite polarity to that set up by the lower windings 3 when energized. Thus it is seen that my motor is electrically 60 bipolar, there being three projecting cores per pole.

The numerals 4, 5 and 6 respectively denote the direct connections between the pairs of magnets A A', B B' and C C'. As is made very clear by the diagram shown in 65 Fig. 4, the three pairs of opposite field coils are Y-connected at a point 7.

With the commutator 10, there are correlated three brushes, respectively denoted by the numerals 11, 12 and 13, the brushes 11 and 12 being substantially one hundred and eighty degrees apart, while the brush 13 is closely adjacent to the brush 12. For the purpose of this explanation the brush 11 75 will be considered negative and the brushes 12 and 13 positive. The brush 11 has connection with one of the motor terminals as indicated at 14, and from the other terminal a wire 15 is extended to the coil C. Wires 16 and 17 respectively establish connection 80 between the brushes 12 and 13 and the coils A' and B'.

The armature shown is of a common double-lap-wound type, and it is to be understood that the armature construction and 85 winding is not claimed as a novel feature of my motor. The novel features of my invention lie in the particular manner of connecting the field coils both with one another and with the motor terminals, and in the 90 use of three brushes having the relation specified. Through the embodiment in my motor of these unusual features, equal efficiency is obtained from the operation of the 95 motor under either a direct or alternating current. It will of course be understood 100 that the poles in the field, the segments in the commutators and the coils in the armature may be varied in number as in any motor.

When supplied with direct current, my 105 motor operates in substantially the same manner as an ordinary series wound D C motor, the direction of current in the armature conductors being constant in a certain direction adjacent to the north poles of the field, and being constant in the other direction adjacent to the south pole of the field.

It may be noted however that the coils A and A' will not be energized except at those instants when the brushes establish a short circuit between two adjacent commutator segments, as is illustrated in Fig. 2.

When my motor is supplied with alternating current, it may be considered to act as a split phase induction motor having a rotating magnetic field.

10 The invention is presented as including all such modifications and changes as properly come within the scope of the following claims.

What I claim is:

15 1. An electric motor, comprising a yoke, a plurality of magnet cores projecting rigidly from the yoke, three sets of Y-connected windings respectively mounted upon said cores, an armature and a commutator having the usual relation, three brushes bearing upon the commutator, conductors extending from two of the brushes to two of the sets of field windings, and conductors extending from the motor terminals respectively to the other brush and other set of field windings.

20 2. An electric motor comprising a yoke, three sets of angularly displaced field windings, an armature and a commutator having the usual relation, three brushes bearing upon the commutator, conductors extending from two of the brushes to two of the sets of field magnet windings, and conductors extending from the motor terminals respectively to the other brush and other set of field windings.

25 3. An electric motor, comprising a yoke, three equal angularly displaced interconnected sets of field coils carried by the yoke, one of the sets having connection with one of the motor terminals, an armature and a commutator connected in the usual relation, and three brushes bearing upon the commutator two of which have electrical connection with

two of the sets of field coils, while the other 45 has connection with the other terminal.

4. An electric motor, comprising a yoke, a plurality of magnet cores projecting therefrom, Y-connected sets of windings mounted upon said cores, the windings of each set 50 being oppositely disposed and series connected, one of said windings being in electrical connection with one of the motor terminals, and three brushes bearing upon the commutator, one of which has electrical connection with the other motor terminal, while the other two are respectively connected to the other two sets of field windings.

5. An electric motor, comprising a double wound armature, three sets of interconnected angularly displaced field windings correlated with the armature in the usual relation thereto, a commutator bearing the usual relation to the armature and brushes bearing upon the commutator, so arranged 65 as to throw the armature windings alternately into action.

6. An electric motor, comprising three sets of angularly displaced Y-connected field coils, one set of the coils having connection with one of the motor terminals, an armature and commutator having the usual relation and three brushes bearing upon the armature two of which are adjacent and are respectively connected to two of the sets of 75 field coils, the third brush being substantially opposite to one of the others and being electrically connected to the other motor terminal.

In testimony whereof I have signed my 80 name to this specification in the presence of two subscribing witnesses.

HOMER E. ADAMS.
